Primary Examiner — Mitchell I. Siegel*(74) Attorney, Agent, or Firm* — Randy K. Chang(57) **CLAIM**

The ornamental design for golf club head, as shown and described.

DESCRIPTION

FIG. 1 is a bottom perspective view of our new design for a golf club head;

FIG. 2 is a bottom sole view thereof;

FIG. 3 is a top view thereof;

FIG. 4 is a front view thereof;

FIG. 5 is a back view thereof;

FIG. 6 is a heel view thereof; and,

FIG. 7 is a toe view thereof.

The broken lines shown are included for the purpose of illustrating unclaimed subject matter and forms no part of the claimed design.
